TELEGRAPH PRINTING SYSTEM

James A. Spencer, Teaneck, N. J., assignor to
 Radio Corporation of America, a corporation of
 Delaware

Application January 21, 1939, Serial No. 252,179

16 Claims. (Cl. 178—4)

This invention relates to printing mechanism for use in radio and wire telegraph systems.

In prior art tape transmitters and printers for simplex telegraphy using an equal length code, it has been necessary to utilize some of the units for local functions of the transmitter and receiver. In multiplex telegraphy it has been the practice to operate two or more transmitter tapes or printers together and perform the local function of one tape transmitter or printer while the next combination is being set up on another.

It is an object of the invention to provide a system that utilizes all the circuit time for carrying equal length code signals and to operate the local mechanism of a device while another combination is being set up on the same device.

Another object is to provide a printing system for a single channel employing an equal length code, in which all the circuit time is used for the code transmission and reception.

Another object is to provide an arrangement for an equal length code by storing a part of a code unit in a sending or receiving device for a sufficient time to permit such device to perform its local operations.

Other objects will appear in the following description, reference being had to the drawings in which:

Fig. 1 is a conventional illustration of the transmitting circuit and associated elements.

Fig. 2 is a view of the code characters for the letters of the alphabet used in the system.

Fig. 3 is an illustration of the current pulses transmitted or received.

Fig. 4 is a conventional illustration of the receiving circuits and associated elements.

Fig. 5 illustrates the battery and terminals.

Fig. 6 is a diagrammatic and skeleton illustration of the printer.

Fig. 7 is an illustration of the type bar operating mechanism.

Referring to Fig. 1, the storing transmitter contains relays I to IX inclusive, the first seven of which are connected to tape transmitter 10. The relays function in connection with a transmitting ring 11 and a commutator 12 having seven contact segments over which sweeps short-circuiting brushes 13, rotating in synchronism with, or at a speed proportional to the distributor in a multiple system, or otherwise caused to rotate at a constant predetermined speed. Inasmuch as the multiple systems and means for maintaining a given speed for the distributors at the transmitter and receiver are old and well known and are specifically not claimed herein,

such parts are not shown, reference, however, is made to patents to Callahan, Mathes and Kahn, No. 2,010,505, and Mathes Patent No. 2,028,375, which contain detail descriptions of such systems.

5 A second ring 14 and commutator 15 having seven segments are swept over by short-circuit brushes 16. These brushes rotate in unison with the brush 13 and in practice are preferably mechanically fastened thereto.

10 The tape transmitter 10 contains seven seeker pins diagrammatically indicated at 17, adapted to pass through perforations in a perforated tape such as is illustrated in Fig. 2. This transmitter is operated by magnet 18 connected to contacts 15 and 6 of commutator 15. These seeker pins are old and well known in the art and are not illustrated but it will be understood that they are resiliently raised against the tape by appropriate mechanism. When a perforation occurs in a 20 tape in accordance with a message, the pins there beneath pass through the perforations and engage the superposed contact members. Since the time code used consists of seven units there are seven of these contact members connected respectively to the coils of relays I to VII.

25 The coils of relays I, II, III and IV are completed to ground directly through return wire 19. The circuit through the coils of relays V, VI and VII are completed through the switch contacts 30 20 when relay IX is energized and thence to ground through return wire 19. Relays V, VI and VII also have holding coils 21, 22 and 23 energized by contacts closed by operation of the respective relays. The energizing circuit of these holding coils includes common conductor 24 and switch contacts 25 controlled by relay VIII. Relay VIII has one terminal connected to the ground wire 19 and the other one to the first contact on commutator 15.

35 40 The coil of relay IX which when energized closes contacts 20, has one terminal connected to the ground wire 19 and the other connected to the third contacts of commutator 15.

45 The operation of the transmitter in Fig. 1 will now be described. It will be understood that the brushes 13 and 14 are rotating at a constant predetermined speed by well known mechanism previously referred to herein, but not illustrated. These brushes engage similarly numbered segments at the same time. Assuming that the brushes 13 and 16 have just engaged contacts No. 5 by their rotation in the direction of the arrows 27, current from positive terminal 18' energizes coil 18 which clears the mechanical parts of the transmitter of previous code com-

binations by withdrawing the seeker pins below the tape, stepping the tape forward and permitting the seeker pins to again move towards the tape.

Let it be supposed that the perforations at this point have been punched for the letter H. By referring to Fig. 2, it will be seen that the second, fifth and sixth seeker pins will pass through the perforations and engage their corresponding contacts. The remaining seeker pins being resiliently pressed against the tape will be prevented from moving against their respective contacts by the absence of perforations. At this time relay II becomes energized because its circuit is completed directly from positive terminal 28 through the seeker pin and contact to ground through conductor 19. The closing of contacts by seeker pins Nos. 5 and 6, however, do not energize the coils of relays V and VI because their circuits are open at contacts 20, relay IX being de-energized. Positive potential is applied to segment 2 on commutator 12 by closure of front contact 29 of relay 2 but it is not transmitted to line because at this time brush 13 is in engagement with contact No. 5. Relays V and VI will not place positive potential on segments 5 and 6 at this time because they have not been energized due to the open contacts 20 on relay IX.

The brushes 13 and 16 continue sweeping over the segments and engage contact members No. 1. Lower contact No. 1 is connected to the coil of relay VIII which becomes energized by current passing from positive terminal 18' through conductor to ground wire 19. This opens contact 25 and deenergizes the holding coils of relays V, VI and VII if those relays have been previously energized. In other words, this is a clearing action. Upper contact No. 1 is engaged by brush 13 on commutator 12 and negative potential is placed on ring 11 and outgoing line 31. This forms portion 34 of the graph in Fig. 3. When the brushes engage contact No. 2 on the commutator a positive pulse 35 is sent out into the line 31 as relay No. II is closed. When the brushes engage contact No. 3 negative pulse 36 is placed on line 31 since back contact 37 is closed. At this time brush 16 being on lower segment 3 of commutator 15, relay IX is energized from positive terminal 18'. This closes contacts 20 and energizes selected relays V and VI. These relays have their holding coils energized at once as relay VIII is now de-energized.

When brush 13 engages segment No. 4 negative pulse 38 is placed on ring 11 and outgoing line 31 because relay IV is de-energized.

When the brushes engage segment No. 5 the upper brush 13 places positive pulse 39 on line 31 because contact 40 is closed, relay V being previously energized. At this same time operating magnet coils 18 are energized by the connecting of the positive terminal 18' through brush 16 to these coils. This lowers the seeker pins from the perforations and steps the tape forward to the next row of perforations which we will assume is for the letter A. As shown by Fig. 2, this will permit the first, third and fourth seeker pins to engage their contacts and energize relays 1, 3 and 4. Positive potential will be applied to segments 1, 3 and 4 to commutator 12 but pulses will not be conveyed to line 31 at this time because the brushes are on segment No. 5. It should be noted that even though the seeker pins have closed the transmitter contacts

for the letter A, transmission of the previous letter H is still uncompleted.

When the brushes engage contact segments No. 6 positive pulse 41 will be applied to line 31 because relay VI was previously energized for the letter H and the segment No. 6 in commutator 12 is connected to the positive terminal through make contact 42.

When the brushes engage segments No. 7 negative pulse 43 will be placed on the line 31 because back contacts 44 are closed. This completes the letter H and as just explained, the tape transmitter has been previously set for transmitting the letter A.

When the brush 13 engages segments No. 1, positive pulse 44, will be placed on outgoing line 31 because relay I is energized. Also, relay VIII is energized by action of brush 16 and contacts 25 are opened. This opens the back contacts 45 of relay V which were closed when this relay became energized through energization of relay IX on previous contact of the brush with segments No. 3. At that time this closed a holding circuit for relay V independent of contacts 20 on relay IX. The back contacts 46, 47, of relays VI and VII were also opened by relay VIII at this time but since the relays VI and VII were not energized in formation of the letter H nothing happens in respect to those relays.

The brushes next engage segments No. 2. Brush 13 thereupon places negative pulse 48 on line 31 as relay II is deenergized. When the brushes engage segments No. 3 positive pulse 49 is placed on line 31 by brush 13 and relay IX is energized by engagement of brush 16 with segment No. 3. This immediately closes the circuit of relays V, VI and VII but since the seeker pins do not engage the contacts for these relays for the letter A nothing further happens.

When the brushes engage segment No. 4 brush 13 places a positive pulse 50 on line 31 because relay 4 is energized. When the brushes engage contact No. 5 negative pulse 60 is placed on line 31 and operating magnet 18 becomes energized which withdraws the seeker pins and steps forward the tape in the printer for the next letter which may be assumed to be N, but it should be again emphasized that even though the next letter N has been selected by the transmitter the cycle for the previous letter A has not been completed. This letter A is completed only when the brushes engage segments 6 and 7 and place negative pulses 61 and 62, respectively, on line 31.

It may be assumed that the next letter after formation of the letter N will be the letter D. The operation of the mechanism will now be clear and it will be unnecessary to trace out in detail the formation of letters N and D but the pulses have been shown in Fig. 3.

It will be seen from the foregoing that the tape transmitter is operated during the time that the fourth, fifth and sixth impulses are stored and hence all seven time units are available for the signal message itself.

The code partially shown in Fig. 2 allots three "marking" units and four "spacing" units to each code character. This has been found to be decidedly advantageous in radio systems, particularly as the omission or addition of one or more units by static or other cause can never form a letter or other signal character which is the case with the five unit Baudot code.

In Fig. 4 I have illustrated the circuit diagram of the receiver. On account of the similarity to the transmitter the operation will be understood

without detail explanation of the various parts but it should be understood that the rings and commutator segments are running synchronously and in phase with those of the transmitter by mechanism old in the art, and not illustrated.

At the transmitter in Fig. 1 positive pulses are sent out for marking and negative pulses for spacing, as already referred to. The receiving circuit, however, is shown as arranged for current pulses for marking and no current for spacing. Therefore, somewhere in the link between the transmitter and receiver the positive and negative pulses will be converted into "on" and "off" indications. In radio circuits this is done at the radio transmitting station before radiation takes place. At the radio receiving station the received pulses are sometimes converted back into negative and positive pulses for line transmission to another point. In wire transmission, the positive and negative pulses may be received directly from the wire 31 at the transmitter. The particular type of transmission is immaterial as far as my invention is concerned. The positive and negative pulses reaching the receiving printer office, in any way, operates the polar relay 63 by energizing the coil 64 connected to the incoming line 65.

The operation of the receiving apparatus is as follows:

Referring to Fig. 4 and assuming that the first negative pulse 34 of the transmitter letter H or other pulse formed therefrom, has arrived at the polarized relay 64, the switch tongue of the relay will be moved against dead contact 66 and no current will flow when brush 13 engages segment No. 1 of commutator 16. Also, no current will flow from commutator 15 at this time.

When positive pulse 35 arrives at relay 64 the relay tongue will be moved against positive contact 67. At this time brushes 13 and 16 will be on segments No. 2 and relay RII will be energized. The energization of this relay closes its own holding circuit to ground through contact 71 of relay RIX and it also energizes selector magnet R2 of the printer (see also Fig. 6). In the printer shown in Fig. 6 the latch and selector mechanism for relay RI is the only one completely illustrated but the constructions in respect to the other relays are exactly the same.

When relay R2 was energized it attracted one end of its armature 73, pivoted in the center, against the tension of its returning spring and projected the opposite end into notch 74 of selector bar 75, there being a selector bar for each selector relay. The armature is held in this position by latch 76 so that when the brush 13 leaves segment No. 2 of the commutator the armature will remain in its operated position. The selector magnets R1 to R7 and their armatures and latches are all secured to the movable carriage 77.

When negative pulses 36 and 38 arrive in succession the switch tongue of polarized relay 64 will be thrown against the dead contact 66 and when brushes 13 and 16 engage contacts No. 3 and No. 4 in succession relays RIII and RIV will not be energized.

When positive pulse 39 arrives relay 64 will engage contact 67 and current will energize relay RV as brush 13 is in engagement with segment No. 5. Relay RIX is also energized by brush 16 engaging segment No. 5. This opens the holding circuit for relays I and IV to clear them for succeeding signals. When brush 13 engages segment No. 6 pulse 41 causes relay RVI to be ener-

gized. Relays RV and RVI energize in succession printer selector magnets R5 and R6 which operate their armatures by projecting their ends into notches (indicated only for relay R1) in selector bars 79 and 80 fragmentarily shown in Fig. 6. These selector bars are broken away but they have a series of properly positioned notches such as notch 81.

When relays R2, R5 and R6 operate their armatures each of them also closes contacts through a cut-out shaft and lever, diagrammatically illustrated as simple switch contacts 81' in Fig. 6 which closes a circuit to relay R8, but as shown in Fig. 4, the circuit is open at relay RVIII. Relay RVIII has its coil connected to segment No. 7 on commutator 15. Therefore, when brush 16 engages segment No. 7 relay RVIII is energized. Relay RVIII opens the holding circuit of relays R5 and R6 clearing those relays for the next signal. Relay RVIII also energized relay R8 which closed switch contacts 82 and energized carriage magnet 83. Armature 84 then moves the printer carriage 87 (the middle portion being shown broken away) towards the left by means of plunger 86.

Selector magnets R1 to R7 and their respective armatures are mounted on carriage 87 and as the carriage is moved to the left the selector bars 75, 79 and 80, are moved therewith because the projecting ends of armatures 73 of selector magnets R2, R5 and R6 engage the edges of notches identical with 74. Shortly before the motion to the left is completed trip 92 engages latch 76 and permits armatures 73 to spring back into place. The armature is freed from friction against the ends of notch 74 at this time by leaf spring 93 entering notch 94 in the three selector bars which snaps the selector bars slightly to the left. Similar trips (not shown) release the other armatures. Selector magnets R, R5 and R6 then resume their normal condition. When the three selector bars reach their extreme left-hand position notches 81 in the three selector bars corresponding to the letter H are in alignment. Pull bar 88 shown more in detail in Fig. 7, is then in position to drop into the aligned notches but it is held from this movement by the printing bail 89 engaging a hump on the pull bar.

When the carriage reaches its extreme movement to the left it opens switch contacts 90 and breaks the continuity of the holding circuit of relay R8. This deenergizes the relay and opens the contacts 82 which in turn deenergizes carriage magnet 83. The carriage return spring 91 thereupon returns the carriage to the right against stop 85.

As the selector bars 75', 79 and 80 moved to the left in the initial motion of the carriage they engaged return lever 95 and turned it around its center point against the tensions of its spring 96. Latch 97 immediately snapped into position and held the return lever so that the selector bars were not returned to the right at that time.

As the return lever 95 snapped into the notch of latch 97 printing contacts 98 closed and printing relay 99 was energized. This closed contacts 100 and energized printing solenoid 101. This solenoid pulls the armature 102 downward with its extension 103 which is pivoted to printing bail 89, the bail being pivoted at an intermediate point 104. This moves the bail upward (Fig. 7) and permits the pull bar 88 to drop into the aligned notches 81 (Fig. 6) in the

selector bars. As it does this the upwardly moving projection 105 engages the shoulder 106 in the pull bar and moves it upwards with the bail. This throws type bar 107 downwards and strikes the type-pallet against the ribbon on platen 108. This prints the letter H.

Just at the time that the armature 102 of the printing solenoid completed its movement projection 109 engaged the latch 97 and permitted the return lever 95 to return the three selector bars to the right whereupon leaf spring 83 snapped into groove 110 which holds these three bars together with the others in their initial position. At about this time projection 111 opens switch contacts 112 and deenergizes the printing relay and the printing solenoid plunger is returned to its initial position by spring 113. This returns the pull bar and brings the printing bail 89 against the hump of the pull bar and moves it outwards clear of the selector bars.

The selected letter H has thus been printed and all mechanism of the printer has returned to the original position. However, the selection of the next transmitted letter was not held up pending the operating of the printing mechanism. Since the holding coils of relays RI and RIV were opened by relay RIX when the brush 16 was on the fifth segment those relays were thereafter available for subsequent signals. The selector magnets assumed their inoperated position before the printer magnet was energized so signals in RI to RIV can be stored in the printer as soon as the brush 13 reaches their corresponding commutator segments. Since the holding circuit of relays RV to RVII was opened when the brush energized the seventh segment, those relays were then made available for further signals. In view of this the printing mechanism has substantially one full revolution of the commutator for completion of the printing operation itself. During this printing operation the signal code reception continues without interruption as the impulses, in effect, are stored in the relays while the printing is completed.

The letters A, N and D will be printed in a manner similar to the letter H by operation of the required combination of selector bars.

Since the printing system of my invention operates independently of the tape transmitters and printers of other channels, its greatest advantage over prior art systems is in single channel printing operations.

I have illustrated circuit arrangements that have been found satisfactory but the invention is not to be limited thereto as various changes could be made without departing from the spirit of the invention.

Having described my invention, what I claim is:

1. In an electric telegraph system for multi-unit equal length code characters, a communication channel, a tape transmitter, relays each having an operating coil and a switch, each coil being connected to said tape transmitter, a commutator having spaced segments each connected to one of said switches, said switch connecting one potential to a segment when the coil is energized and to another potential when it is de-energized, a brush adapted to move over said segments and connect them successively to the outgoing line of said communication channel, at least one of said relays being a storing relay having a holding coil and a switch

connected thereto to be closed when the operating coil is energized, a second commutator having spaced segments, a brush adapted to run in synchronism with the first mentioned brush

5 for connecting the last mentioned segments successively to a potential source, an additional relay having its operating coil connected to a segment of the second mentioned commutator and adapted when energized to open the said 10 holding circuit, a further relay having its operating coil connected to a segment of the second mentioned commutator and adapted, when energized, to close the circuit of the operating coil of said storing relay, and an operating coil 15 for moving the tape of the transmitter, the last mentioned coil being connected to a segment of the second mentioned commutator.

2. In an electric telegraph system for multi-unit equal length code characters, a communication channel, a tape transmitter having contact closers, a series of relays each having an operating coil, a switch tongue and two switch contacts, said coil being connected to one of

20 said contact closers, said switch contacts being connected to opposite terminals of a potential source, and said switch tongue being in engagement with one of said switch contacts when the said coil is energized and with the other when it is de-energized, a commutator having spaced segments each connected to one of said switch tongues, a brush adapted to move over said segments and connect them successfully to the outgoing line of said communication channel, a number of relays being storing relays each

25 having a holding coil containing a switch adapted to be closed when the operating coil is energized, a second commutator having segments spaced similarly to the first, third and fifth segments of the first mentioned commutator, a brush adapted to run in synchronism with the first mentioned brush for connecting the last mentioned segments successively to a potential source, an additional relay having its operating coil connected to a segment of the second men-

30 tioned commutator and adapted when energized to open the circuit of said holding coil, a further relay having its operating coil connected to another segment of the second mentioned commutator and adapted, when energized, to close

35 the circuit of the operating coils of the storing relays, and an operating coil for the tape transmitter, the last mentioned coil being connected to the remaining segment of the second mentioned commutator, said coil moving the tape to set up new code combinations when the last mentioned segment is contacted by its brush.

3. In an electric telegraph system for seven-unit equal length code characters, a communication channel, a tape transmitter having seven contact closers, seven relays each having an operating coil, a switch tongue and two switch contacts, said coil being connected to one of said contact closers, said switch contacts being connected to opposite terminals of a potential source and said switch tongue being in engagement with one of said switch contacts when the said coil is energized and with the other when it is de-energized, a commutator having seven segments each connected to one of said switch

60 tongues, a brush adapted to move over said segments and connect them successively to the outgoing line of said communication channel, three of said relays each having a holding coil and a switch therefore adapted to be closed when

the operating coil is energized, a second commutator having three segments, circumferentially positioned similarly to the first, third and fifth segments of the first commutator, a brush running in synchronism with the first mentioned brush and adapted to connect the last mentioned segments successively to a potential source, an eighth relay having its operating coil connected to the first segment of the second mentioned commutator and adapted when energized to open the circuit of said holding coils, a ninth relay having its operating coil connected to the third segment of the second mentioned commutator and adapted, when energized, to close the circuit of the operating coils of the said three relays, and an operating coil connected to the fifth segment of the second mentioned commutator for moving the tape of the tape transmitter to a new position whereby new circuit combinations are set up by the tape transmitter when the fifth segment has been contacted by the brushes without destroying the fifth, sixth and seven circuit combinations previously set up thereby.

4. In an electric printing telegraph system for a multi-unit equal length code, an incoming line carrying successive pulses representing the units of each code character, a commutator having as many segments as the number of units in said code characters, means for cyclicly connecting the incoming line successively to said segments, a printer having selector bars, an operating magnet for moving the selector bars, a selector relay having an operating coil connected to each of the segments of said commutator, a selector magnet having means for coupling said operating magnet to the selector bars and means for continuing the energization of a plurality of the selector relays after the incoming line is disconnected from their operating coils, and means for energizing the operating magnet after a plurality of the selector relays are de-energized.

5. In an electric printing telegraph system for a multi-unit equal length code, an incoming line for carrying successive pulses representing the units of each code character, a commutator having as many segments as the number of units in said code characters, means for cyclicly connecting the incoming line successively to said segments, a printer having selector bars, an operating magnet for moving the selector bars, a selector relay having an operating coil connected to each of the segments of said commutator, a selector magnet having means for coupling said operating magnet to the selector bars and means for continuing the energization of a plurality of the selector relays after the incoming line is disconnected from their operating coils and means for energizing the operating magnet after a plurality of the selector relays are de-energized.

6. In an electric printing telegraph system for a multi-unit equal length code, an incoming line for carrying successive pulses representing the units of each code character, a commutator having as many segments as the number of units in said code characters, means for cyclicly connecting the incoming line successively to said segments, a printer having selector bars, and an operating magnet for moving the selector bars, a relay having an operating coil connected to each of the segments of said commutator having means for coupling said operating magnet to the selector bars, the relays connected to the

segments assigned to the initial units of the code characters having holding coils, a second commutator having two spaced segments, means for cyclicly connecting the segments of the last mentioned commutator to a potential source, means connected the leading segments of the last mentioned commutator for opening the circuit of said holding coils, and means for connecting the trailing segment of the last mentioned commutator to said operating magnet.

7. In an electric printing telegraph system for a multi-unit equal length code, an incoming line for carrying successive pulses representing the units of each code character, a commutator having as many segments as the number of units in said code characters, means for cyclicly connecting the incoming line successively to said segments, a printer having selector bars, a selector magnet for each selector bar and an operating magnet for moving the selector bars, a relay having an operating coil connected to each of the segments of said commutator for energizing said magnets, the relays connected to the segments assigned to the initial units of the code characters having holding coils, a second commutator having two spaced segments, means for cyclicly connecting the segments of the last mentioned commutator to a potential source, means connected to one of the segments of the last mentioned commutator for opening the circuit of said holding coils, and means for connecting the other segments of the last mentioned commutator to said operating magnet.

8. In an electric printing telegraph system for a multi-unit equal length code character, an incoming line for carrying successive pulses representing the units of each code character, a commutator having as many segments as the number of units in said code characters, means for cyclicly connecting the incoming line successively to said segments, a printer having selector bars, a selector magnet for each selector bar and an operating magnet for moving the selector bars, a relay having an operating coil connected to each of the segments of said commutator for energizing said magnets, the relays connected to the segments assigned to the initial units of the code character having holding coils, a second commutator having two spaced segments, means for cyclicly connecting the segments of the last mentioned commutator to a potential source, means connected to one of the segments of the last mentioned commutator for opening the circuit of said holding coils, and means for connecting the other segment of the last mentioned commutator to said operating magnet.

9. In an electric printing telegraph system for seven-unit length code characters, an incoming line for carrying successive pulses representing the units of each code character, a commutator having seven segments, means for cyclicly connecting the incoming line successively to said segments, a printer having seven selector bars, seven selector magnets and an operating magnet for moving the selector bars, four relays having operating coils connected to the first four of the segments of said commutator for energizing four of said selector magnets, said relays having holding coils, means to connect the remaining segments of said commutator to the remainder of said selector magnets, a second commutator having two segments circumferentially spaced similarly to the fifth and seventh segments of the first mentioned commutator, means

for cyclicly connecting the segments of the last mentioned commutator to a potential source, means connected to one of the segments of the last mentioned commutator for opening the circuit of said holding coils, and means for connecting the other segment of the last mentioned commutator to said operating magnet.

10. In an electric printing telegraph system for seven-unit equal length code characters, an incoming line for carrying successive pulses representing the units of each code character, a commutator having seven segments, a brush adapted to connect the incoming line successively to said segments, a printer having seven selector bars, seven selector magnets and an operating magnet for moving the selector bars, seven relays having operating coils connected to the segments of said commutator for energizing said selector magnets, said relays holding coils, a second commutator having two segments circumferentially spaced similarly to the fifth and seventh segments of the first mentioned commutator, a brush moving synchronously with the first mentioned brush adapted to connect the segments of the last mentioned commutator to a potential source, another relay having an operating coil connected to one of the segments of the last mentioned commutator adapted, when energized, to open the circuit of the holding coils of the first four of the first mentioned relays, a further relay having means to open the circuit of the holding coils of the remainder of the first mentioned relays and to close the circuit of said operating magnet and means to connect said further relay to the other segment of the last mentioned commutator.

11. In an electric telegraph system for multi-unit equal length code characters, a communication channel, a plurality of relays having coils and switch tongues, part of said relays having means for holding them in operated position, a distributor for continuously connecting said switch tongues successively to said channel in successive cycles, a code transmitter having switches in circuit with said coils, an additional switch in circuit with coils of the last mentioned relays, means for operating said code transmitter to close the first mentioned switches of the coils for a new code combination before the transmission cycle of the previous code combination is completed, means for closing the additional switch in the next succeeding cycle before the switch tongues of the last mentioned relays are connected to the said channel in that cycle, and means for causing the first mentioned means to restore the relays to inoperated position before said additional switch is closed.

12. In an electric telegraph system for multi-unit equal length code characters, a communication channel, a plurality of relays having coils, switch tongues and pairs of contacts, part of said relays being storing relays with means for holding them in operated position, the switch tongues being normally in engagement with one of the contacts, a distributor for continuously connecting said switch tongues successively to said channel in successive cycles, a code transmitter having switches in circuit with said coils, an additional relay having a switch in circuit with coils of said storing relays, means for operating said code transmitter to close the first mentioned switches of the coils for a new code combination before the transmission cycle of the previous code combination is completed, means for energizing the additional relay in the next succeeding cycle before the

fore the switch tongues of the last mentioned relays are connected to the said channel in that cycle, the closing of said additional switch energizing coils for moving the switch tongues into engagement with the other contacts of said pairs, and a further relay energized before said additional relay for causing the first mentioned means to restore the relays to inoperated position.

13. In an electric telegraph system for multi-unit equal length code characters, a communication channel, a plurality of relays having operating coils, switch tongues and positive and negative contacts, the switch tongues being normally in engagement with one of said contacts, a distributor for continuously connecting said switch tongues successively to said channel in successive cycles, a code transmitter having switches in circuit with the operating coils, an additional switch in circuit with the operating coils of a part only of said relays, the last mentioned relays having holding coils, a clearing switch in circuit with each of the holding coils, means for operating said code transmitter to close the first mentioned switches for a new code combination before the transmission cycle of the previous code combination is completed, means for closing the additional switch in the next succeeding cycle before the switch tongues of the last mentioned relays are connected to the said channel in that cycle, the closing of the additional switch energizing the operating coils for moving the switch tongues into engagement with the other contact, and means for opening the clearing switch in said next succeeding cycle before the closing of the additional switch.

14. In an electric telegraph system for multi-unit equal length code characters, a communication channel, a plurality of relays having operating coils and switch tongues, part of said relays being storing relays, a distributor for continuously connecting said switch tongues successively to said channel in successive cycles, a code transmitter having switches in circuit with said coils, an additional relay having a switch in circuit with the operating coils of said storing relays, the storing relays having holding coils, a clearing relay having a switch in circuit with said holding coils, means for operating said code transmitter to close the first mentioned switches for a new code combination before the transmission cycle of the previous code combination is completed, means for energizing the clearing relay in said next succeeding cycle and means for energizing said additional relay in that cycle after the energization of the clearing relay.

15. In an electric telegraph system for multi-unit equal length code characters, a communication channel, a plurality of relays having coils and switch tongues, a distributor for continuously connecting said switch tongues successively to said channel in successive cycles, a code transmitter having switches in circuit with said coils, an additional switch in circuit with coils of a part only of said relays, means for operating said code transmitter to close the first mentioned switches for a new code combination before the transmission cycle of the previous code combination is completed, means for closing the additional switch in the next succeeding cycle before the switch tongues of the last mentioned relays are connected to the said channel in that cycle, and means for restoring the last mentioned relays to normal in said next succeeding cycle before the additional switch is closed in that cycle.

16. In an electric telegraph system for multi-

unit equal length code characters, a communication channel, a plurality of relays having coils, switch tongues and pairs of contacts, the switch tongues being normally in engagement with one of the contacts, a distributor for continuously connecting said switch tongues successively to said channel in successive cycles, a code transmitter having switches in circuit with said coils, an additional switch in circuit with the coils of a part only of said relays, means for operating 5 said code transmitter to close the first mentioned switches of the coils for a new code combination

before the transmission cycle of the previous code combination is completed, means for closing the additional switch in the next succeeding cycle before the switch tongues of the last mentioned relays are connected to the said channel in that cycle, the closing of said additional switches energizing coils for moving the switch tongues into engagement with the other contacts, and means for restoring the last mentioned relays to normal in said next succeeding cycle before the additional switch is closed in that cycle.

JAMES A. SPENCER.
